UNITED STATES PATENT OFFICE.

CHARLES V. WILGUS, OF KINGSTON, PENNSYLVANIA, ASSIGNOR TO THE ADDER MACHINE COMPANY, OF WILKES-BARRE, PENNSYLVANIA, A CORPORATION OF PENNSYLVANIA.

CALCULATING-MACHINE.

1,133,596.

Specification of Letters Patent. Patented Mar. 30, 1915.

Application filed July 12, 1913. Serial No. 772,639.

To all whom it may concern:

Be it known that I, CHARLES V. WILGUS, a citizen of the United States, residing at Kingston, Luzerne county, Pennsylvania, have invented new and useful Improvements 5 in Calculating-Machines, of which the following is a specification.

This invention relates to calculating machines, and more particularly to the registering or accumulating mechanism thereof, 10 and its associated transfer or carrying mechanism.

In calculating machines of the type to which this invention is, in the present instance applied, though the use of said invention is not confined thereto, the registers or counters are cleared by first engaging the counters and their drive members, after which a restraining and restoring bail is 20 withdrawn to permit the drive members to advance, under spring tension, and turn the counters until the latter are arrested by the contact of stops thereon, with an abutment member previously shifted into the paths 25 thereof. The stops arrest the counters when they display ciphers at the reading line. The withdrawal of the restraining and restoring bail, to which the springs which advance the drive members may be connected, 30 further tensions such springs until, at the end of the initial stroke, the springs exert considerable pressure through the drive members, to hold the stops on the counters firmly against the abutment member, and in 35 so doing, store turning moment in the counters. After the arrest of the counters at zero, the latter and the drive members are disconnected, and the drive members retired to initial position. The counters are 40 arranged to turn freely on their support and the sudden release from their drive members, frees the counters to the action of the turning moment stored therein, which tends to cause the counters to rebound from 45 the abutment member and display a figure other than zero at the reading line. This is known to the trade, as "throwing (or kicking) in ones." To overcome this disadvantage, spring-pressed detents have been pro- 50 vided to engage the teeth of ratchets fixed to turn with the counters, as the latter and their drive members are disengaged, but if the machine be subjected to rapid and violent operations, or in case of rapidly op-

erating motor-driven machines, the turning 55 moment referred to, might be sufficient to overcome the detents and effect an undesired registration by the counters.

One object of this invention is to positively lock the counters in zero position in 60 such clearing operation, and I accomplish this result, in the present instance, by locking the detents against yielding to such stored energy.

Another object of this invention is to prevent a possible under-addition on the accumulating mechanism, due to the non-operation of the carrying or transfer mechanism, which object, in the present instance, is attained by positively operating the re- 65 setting and carry-deferring devices to prevent an excess throw thereof, thereby 70 rendering the carrying mechanism more efficient in operation.

To these and other ends, therefore, this 75 invention comprises new and useful devices which will be hereinafter more fully set forth and pointed out in the claims.

In the accompanying drawings, Figure 1 is a side view, partly broken away, showing the well known Wales calculating machine, to which one embodiment of the invention is applied, parts being omitted. Fig. 2 is a similar view, showing the clearing key depressed, to shift the abutment into 85 the paths of the stops on the counters, with the counters connected with their drive members, in a clearing operation. Fig. 3 is a detail side view, showing the manner in which turning moment is stored in the 90 counters during a clearing operation, the drive member being advanced and its spring tensioned by the restraining and restoring bail. Fig. 4 is a perspective of the invention. Fig. 5 is a slight modification of the 95 locking detent. Fig. 6 is a detail sectional view, showing the accumulating and carry- 100 ing or transfer mechanism, with the lock for preventing the rebound of the counters in a clearing operation, the parts being in idle position. Fig. 7 is a similar view, showing a carry taking place, and illustrating the manner in which the locking detent yields during such operation.

Some of the parts shown in the drawings 105 and hereinafter referred to, are likewise shown in U. S. patents to Wales, 794,205, July 11, 1905; and 797,032, August 15, 1905;

McFarland, 842,232, January 29, 1907; and McFarland & Wales, 880,157, February 25, 1908, to which reference is made for a more complete description.

5 Side frames 1, (Fig. 1) of which one only is shown, support a key-board mechanism, having several rows of keys 2, and an accumulating or registering mechanism controlled thereby. Depressing a key 2, sets a stop 3 in the path of a rack or drive member 4, mounted on front and rear arms 5 and 6, Fig. 3. The stop, when set, displaces a detainer 7, (Figs. 3, 6 and 7) normally lying in the path of said drive member to arrest the latter. Turning a main drive shaft 8, (Figs. 1 and 2) on its forward stroke, withdraws a restraining and restoring bail 9 (Figs. 3, 6 and 7) to free the drive members to the action of their springs 10, which advance the respective drive members until the latter are arrested either by a stop 3 or a detainer 7, providing no stop has been set in the path of a drive member.

25 The drive springs 10 may be connected with the restraining and restoring bail 9, (Fig. 3) to be tensioned upon the withdrawal of said bail.

30 An axle 11, (Fig. 1) mounted in arms 12 pivoted at 13 to the opposite side frames 1, supports a series of counters 14 adapted to turn freely thereon, each counter having a pinion 15, (Fig. 3) and a ratchet 16 fixed to turn therewith.

35 Props 17, (Fig. 1) secured to the arms 12 rest on a trip rod 18 supported by radius bars 18^a from a cross shaft 51, to normally support the counters above their respective drive members 4 and out of engagement therewith.

40 Legs 21 journaled on the axle 11 lie in line with seats 22 on the side frames 1, and when the main drive shaft 8, on its forward stroke, lowers the trip rod 18 and the props 17, through links 19 and arms 20 connecting the trip rod with the main drive shaft, the legs contact the seats at the outset of such stroke and detain the counters in idle position until the drive members 4 have completed their advance, whereupon, as the 45 main shaft approaches the limit of its forward stroke, the trip rod strikes the forward end walls of slots in bridle links 23 connected to the respective legs 21 to draw the latter off their seats 22, (see Fig. 2) and permit the counters to drop into engagement with the drive members. The main drive shaft 8, on its return stroke, swings the restraining and restoring bail 9 against the 50 drive members 4 or their front arms 5, to 55 retire said members. The drive members, on their return, rotate the counters 14 to register thereon an amount corresponding to the values of the keys depressed. The main drive shaft 8, on its return, also restores the 60 trip rod 18, which at first swings idly until

the drive members 4 have been retired, after which said trip rod contacts the upper ends of slots in the props 17 to raise the latter and thereby disengage the counters from their drive members. The legs 21 rise with the counters, and springs 24 shift the legs into line with their seats 22 when the lower ends of the legs have cleared said seats.

70 In case the amount registered on the counters is larger than the individual capacities of the counters, carrying mechanism (Figs. 6 and 7), is provided to transfer the tens (assuming that the decimal system is used), to the counters to the left of those whose capacities are exceeded by the registered amount. This carry is arranged to take place after the drive members 4 have operated the counters 14, and the latter have been disengaged from their drive members, and corresponds generally with that form shown in U. S. patent to C. Wales, No. 880,157, dated February 25, 1908, to which reference is made for a more complete explanation thereof. Suffice it to say, that as a counter, driven by its rack 4 in an accumulating operation, turns to display a cipher at the reading line, a cam 25 turning with the wheel, strikes and rocks a trigger 26 pivoted on a cross bar 27 and having a stop 28 which supports and locks the forward arm of a rocking lever 29 against the tension of a spring 30. A carrying pawl 31 is mounted on the rear arm of said lever, and when the trigger 26 is displaced, the spring 30 thrusts said pawl against the ratchet 16 fast with the counter to the left of that which tripped the trigger, to turn said left hand counter one step (Fig. 7).

90 In case the trigger 26 is stripped by the cam 25 on the right hand counter prior to the disengagement of the counters and racks, the carrying action is deferred until after the disengagement of the racks and counters. This, I accomplish, by restraining the effective carrying action of the rocking levers 29, through the medium of a restraining rod 32 (Figs. 6 and 7) mounted in resetting arms 33 journaled on a cross bar 34 and connected by slotted links 35 to the rear arms of said carrying levers 29.

95 The main drive shaft 8, on its forward stroke, swings the trip rod 18 to wipe rolls 36 journaled thereon, over abrupt cams 37 merging into dwells 38, formed on the resetting arms 33, to depress said arms and shift the restraining rod 32 to a point near the lower ends of the slots 39 in the connecting links 35, and thus prevent an effective carrying operation of the carrying levers 29, even though the levers may be 100 tripped by the displacement of their triggers. A slight play is allowed the levers 29, however, to enable their drive springs 30 to rock their forward arms into the paths of the triggers 26 when the latter are dis- 105 110 115 120 125 130

placed, to prevent the return of the triggers until after the carrying mechanism has operated and has been reset. The tripped lever 29 on such preliminary throw, is arrested by the contact of the lower end wall of slot 39 of its connecting link 35 with the restraining rod 32. (Fig. 7.)

Heretofore, the rolls 36, on their return stroke, retraced their travel over the dwells 38 and just prior to the return of the main drive shaft to home position, but after the disengagement of the counters and drive members, the rolls rode off the cams 37 to enable the springs (not shown) to return the resetting arms 33, and thereby shift the restraining rod 32 in the slots 39 of connecting link 35.

The drive spring 30 of the carrying lever which has been freed by the displacement of the trigger, shifts the lever 29 to hold the end wall of the slot 39 of its link 35 against the restraining rod 32, and as the latter returns to normal position at the end of the return stroke of the main drive shaft, when the rolls ride off the cams, it permits the drive spring to complete the rocking throw of its carrying lever and thrust its carrying pawl 31 against the ratchet 16 to turn or kick the left hand counter one step. The locking rod 32 returns suddenly, owing to the abrupt contour of the cam 37, so that the carrying operation takes place instantly. The tripped carrying lever 29 is reset on the next operation, in the well known manner.

The carry-restraining and resetting mechanism above set forth, is substantially that disclosed in Wales Patent, 880,157, before referred to, but with the open cams on the resetting arms 33, shown in said patent, there was a possibility, when the main drive shaft 8 was given a sharp, quick, jerky operation, that the rolls 36 in wiping rapidly over the cam 37, might impart sufficient impetus to the arms 33 to cause them to descend below their lowest normal position, and to take up the play allowed the connecting links 35 relatively to the restraining rod 32 when the carrying levers 29 were first tripped. In other words, the spring-restored resetting arms 33 might be driven below the path of travel of the rolls 36 on the trip rod 18, and could only be arrested by the restraining rod 32 when it struck the lower ends of the slots 39 in the connecting links 35. Under such conditions, the tripped carrying lever would not be permitted to shift into the path of its trigger to block the return thereof to effective position, and the restoring spring 40 would have time to return the trigger to effective position before the carrying lever could operate, with a resulting under-addition. To avoid this disadvantage, I have dispensed with the springs formerly used to restore the resetting arms 33, and have arranged cams 41 on the arms

33, over the cams 37 and corresponding thereto. Therefore, instead of depending upon springs (not shown) to lift the resetting arms 33 as the rolls 36 release the abrupt cams 37, I provide lifting cams 41 70 against which the rolls 36 wipe on their return, to positively lift the resetting arms 33, such cams 41 also operating by contact with the rolls 36, to prevent any excess throw of the resetting arms on the initial 75 stroke. In effecting this improvement, I have substituted the cam slot 42 for the open cams of the prior patent, and have placed the rolls 36 in said slots. With this improved form of mechanism, the main shaft 80 8, on its forward stroke, positively depresses the resetting arms to the desired point and upon its return stroke, positively lifts or restores them to idle position, the throw or swing of said resetting arms being constant 85 instead of variable.

A clearing key 43 (Figs. 1 and 2) is provided for use when it is desired to restore the counters to zero position in readiness for another example. Depression of said clearing key 43 (Fig. 2) rocks a setting lever 44, one arm 45 of which is connected at 46 with a draft bar 47 which contacts a projection 48 on an adjustable abutment member 49, to shift the latter into the paths of stops 50 90 95 fast with the counters. Said abutment member may be journaled on a cross rod 49a. Said stops may have the tripping cams 25 formed thereon. Besides adjusting the abutment member in the paths of the stops 50, 100 said shifting bar also displaces the detainers 7 in the manner common to the Wales calculating machine.

The setting lever 44 is fast on a cross shaft 51 which is turned thereby to rock a somewhat similar lever (not shown) on the opposite side of the machine. These levers are connected by links 52 with the respective legs 21, and the levers operate to displace the legs 21 relatively to their seats 22. 105 110

Turning the main drive shaft 8 on its forward stroke, swings the trip rod 18 to lower props 17 and the series of counters 14, together with the legs 21 which latter, being displaced, remain ineffective, and the engagement of the counters and their drive members 4 occurs at the outset of the forward stroke instead of near the end thereof, as in an adding operation. After such engagement, the main drive shaft 8 withdraws the restraining and restoring bail 9 from the drive members 4 to permit the latter to advance, and turn the counters until the stops 50 contact the abutment member 49, at which time ciphers are displayed at the reading line (Fig. 2). 115 120 125

The counters are disengaged from their drive members at the outset of the return stroke of the main drive shaft, after the manner shown and described in patent to 130

McFarland, 842,232, January 29, 1907, after which the restraining and restoring bail 9 retires the drive members. During such return stroke, but after the disengagement 5 of the counters and drive members, the abutment member 49 is released and returns to idle position.

Owing to the ease with which the counters turn on their supporting axle 11, safe-
guards are provided to prevent over- or
under-rotation of the counters, due either
to intention or accident, during different op-
erating conditions. One such safe-guard
comprises a series of detents 55 journaled on
15 a cross rod 56, and spring-pressed to seat
between adjacent teeth of ratchets 16 to
positively hold the counters against back-
ward rotation, and frictionally against for-
ward rotation, when the counters are in idle
20 position. The detents also center the pi-
nions 15 and the counters, so that the teeth
of the pinions engage cleanly with their
drive racks 4, without rolling, when the
counters drop into their racks. The springs
25 57 cause the detents 55 to follow the coun-
ters part way as they drop, to guide the
counters and hold them against undesired
rotation until engaged with their drive mem-
bers. The tails 59 of the detents contact a
30 cross rod 59^a to limit the throw of the de-
tents. As the counters restore, they meet
the detents which settle in their seats be-
tween the teeth of their ratchets and cen-
ter the counters as the latter arrive at idle
35 position.

The main shaft 8, when at the end of its forward stroke, (Figs. 2 and 3) in a clearing operation, has withdrawn the restraining and restoring bail 9 to its farthest limit
40 and may place the highest possible tension on various drive springs 10. These springs exert a considerable pull on the drive mem-
bers 4, which pull is transmitted through
the pinions 15 to the counters 14 and presses
45 the stops 50 forcibly against the abutment
49. As a result of this stress on the coun-
ters, the latter tend to rebound or turn for-
wardly at the moment of disengagement
from their drive members, and at that mo-
50 ment, the detents 55 have not settled firmly
between the teeth of the ratchets 16. Conse-
quently, in rapid operations, such as repeat
operations, for example, the potential en-
ergy stored in the counters by such stress
55 might sometimes be sufficient to turn the
counters past the detents, which would yield
to permit such rotation, and display a fig-
ure other than zero at the sight opening,
after a supposed clearing operation. To
60 remedy this disadvantage, I have provided
means to prevent the detents 55 from yield-
ing away from the counters during a clear-
ing operation, and to this end, I, lock the
detents in effective position by interposing
65 latches 58 in their paths, (Figs. 2, 3 and 4).

Preferably, such latches 58 are mounted on the abutment member 49, (see Fig. 4) and normally remain idle.

Depression of the clearing key 44 to set the abutment member to effective position, 70 also shifts the latches into the paths of the tails 59 of the detents 55 to lock the detents rigidly and positively against yielding. The ratchets 16 approach the detents closely enough to render the latter effective, before 75 the pinions 15 become disengaged from their drive members.

The necessity of permitting the counters to advance one step in carrying operations, 80 prevents the use of an immovable detent. In such carrying operation, which takes place after the counters are disengaged from their drive members, as the counter turns to register the carry, its detent 55 rides over one tooth and settles in the adjacent space 85 to center the counter relatively to the reading line (Fig. 7). The latch 58 when idle, lies opposite a recess 65 in the tail of said detent to enable the latter to yield away from the counter as the latter is turned 90 by its carrying pawl. The rear arm of the carrying lever 29 rocks downwardly when being reset, and drags its pawl backwardly over the teeth of ratchet 16, but the detent 55 prevents backward rotation of the counter. 95

Fig. 5 shows a slight modification of the detent 55 wherein, instead of employing a roll 60 and pin 61 on the nose of the detent, the entire detent is made in one piece, thus producing a less expensive structure from a manufacturing stand-point, 100 since it eliminates two extra parts and assembly operations, and also provides a stronger and more durable construction. The nose 62 of the modified form of detent 105 fits or seats between two teeth of the ratchet 16 and in addition, is forked or provided with a slot 63 having divergent walls, to embrace a tooth on the ratchet, one of said walls being extended, as at 64, to form a 110 guide along which the tooth rides until entered in the slot, thereby centering the counter.

Other changes may be made in the form and arrangement of the several parts disclosed without departing from the spirit and scope of this invention. 115

What I claim as new, is:

1. In a calculating machine, the combi-
nation with a counter; drive means therefor; 120
and a stop on the counter; of an abutment
shiftable into and out of the path of the
stop; a detent to prevent rotation of the
counter when the latter is disengaged from
its drive means; and means to positively lock 125
the detent in effective position.

2. In a calculating machine, the combi-
nation with a counter; and means to clear the
counter; of a detent to prevent accidental 130
rotation of the counter after it has been

cleared; and means to positively lock the detent in effective position.

3. In a calculating machine, the combination with a counter; drive means therefor; a stop on the counter; and an abutment shiftable into the path of the stop on a clearing operation; of a recessed detent to prevent rotation of the counter; and a latch shiftable into and out of locking relation with said detent to positively hold the latter against rocking.

4. In a calculating machine, the combination with a counter; drive means therefor; and a stop on the counter; of an abutment shiftable into and out of the path of the stop; a detent to prevent rotation of the counter when the latter is disengaged from its drive means; and means shiftable with the abutment to positively lock the detent in effective position.

5. In a calculating machine, the combination with a counter; drive means therefor; and a stop on the counter; of an abutment shiftable into and out of the path of the stop; a detent to prevent rotation of the counter when the latter is disengaged from its drive means; and a latch carried by the abutment to positively lock the detent in effective position when the abutment is shifted to its operative position.

6. In a calculating machine, the combination with a counter; drive means therefor; and a stop on the counter; of an abutment shiftable into and out of the path of the stop; a detent to prevent rotation of the counter when the latter is disengaged from its drive means; means to positively lock the detent in effective position; and a key to control both the abutment and detent-locking means.

7. In a calculating machine, the combination with a counter; drive means therefor; and means to arrest the counter at zero in a clearing operation; of key-controlled means, to positively lock the counter at the time of disengagement of the counter and its drive means in a clearing operation.

8. In a calculating machine, the combination with a counter; drive means therefor; and means to arrest the counter at zero in a clearing operation; of devices to positively lock the counter at the time of disengagement of the counter and its drive means, in a clearing operation; and means to release the lock upon the completion of the operation.

9. In a calculating machine, the combination with a counter; drive means therefor; and means to arrest the counter at zero in a clearing operation; of key-controlled devices to positively lock the counter at the time of disengagement of the counter and its drive means in a clearing operation; and means to release the lock upon the completion of the operation.

10. In a calculating machine, the combi-

nation with a counter; drive means therefor; a stop on the counter; and an abutment shiftable into the path of the stop on a clearing operation; of a recessed detent to prevent rotation of the counter; and a latch normally lying opposite said recess, to permit the detent to yield, as the counter is turned in a carrying operation, and shiftable into locking relation with said detent to prevent such yielding after a clearing operation of the counter.

11. In a calculating machine, the combination with a counter; drive means therefor; carrying mechanism; a stop on the counter; and an abutment shiftable into the path of the stop to arrest the counter in zero position; of a detent to hold said counter in zero position; and a latch, normally idle to permit the detent to yield when the counter is turned by the carrying mechanism; said latch shiftable into locking relation with said detent to prevent such yielding at other times.

12. In a calculating machine, the combination with a counter; drive means therefor; carrying mechanism; a stop on the counter; and an abutment shiftable into the path of the stop to arrest the counter in zero position; of a detent to hold said counter in zero position; a latch, normally idle to permit the detent to yield when the counter is turned by the carrying mechanism, said latch shiftable into locking relation with said detent to prevent such yielding at other times; and means operable at will to shift the abutment and latch to effective positions.

13. In a calculating machine, the combination with a counter; drive means therefor; carrying mechanism; a stop on the counter; and an abutment shiftable into the path of the stop to arrest the counter in zero position; of a detent to hold said counter in zero position; a latch, normally idle to permit the detent to yield when the counter is turned by the carrying mechanism, said latch shiftable into locking relation with said detent to prevent such yielding at other times; and a clearing key to shift the abutment and latch to effective positions.

14. In a calculating machine, the combination with a counter; drive means therefor; carrying mechanism; a stop on the counter; and an abutment shiftable into the path of the stop to arrest the counter in zero position; of a detent to hold said counter in zero position; and a latch carried by the abutment, and normally idle to permit the detent to yield when the counter is turned by the carrying mechanism, said latch shiftable into locking relation with said detent to prevent such yielding at other times.

15. In a calculating machine, the combi-

- nation with a series of counters; drive members therefor; stops on the respective counters; and a key-controlled abutment member shiftable into and out of the paths of the stops; of a series of detents for the counters; and a series of latches shiftable into and out of locking relation with the detents.
16. In a calculating machine, the combination with a counter; drive means therefor; and a toothed member fast with the counter; of a detent to hold said counter where adjusted, and including a nose to seat in the interdental spaces of the toothed member, and having a slot to embrace a tooth thereof; one of the walls of said slot being extended to form a guide to direct the tooth into the slot.
17. In a calculating machine, the combination with a counter; drive means therefor; and a toothed member fast with the counter; of a detent to hold said counter where adjusted, and including a nose having a slot with divergent walls to guide and embrace a tooth on said member.
18. In a calculating machine, the combination with a counter; drive means therefor; and a toothed member fast with the counter; of a detent to hold said counter where adjusted, and including a nose to seat in the interdental spaces of the toothed member, and having a slot with divergent walls to embrace a tooth thereof.
19. In a calculating machine, the combination with a carrying mechanism; of means to defer the action of the carrying mechanism, including a resetting arm; and means to positively drive said arm in both directions.
20. In a calculating machine, the combination with a carrying mechanism; means to lock said mechanism ready for operation; and means to release said locking means; of means to defer the action of said carrying mechanism; including a shiftable member loosely connected therewith; and means to positively shift said member through a stroke of predetermined length.
21. In a calculating machine, the combination with a carrying mechanism; means to lock said mechanism ready for operation; and means to release said locking means; of means to defer the action of said carrying mechanism, including a shiftable restraining member loosely connected therewith; and means to positively arrest the shiftable member, at the end of its initial stroke.
22. In a calculating machine, the combination with a carrying mechanism normally

held against operation; and means to trip the carrying mechanism for operation; of means to defer such operation, including a restraining member loosely connected with the carrying mechanism to afford the latter a slight preliminary throw when tripped; and positively-operating means to impart a stroke of predetermined length in both directions to said restraining member.

23. In a calculating machine, the combination with a carrying mechanism normally held against operation; and means to trip the carrying mechanism for operation; of means to defer such operation, including a restraining member loosely connected with the carrying mechanism to afford the latter a slight preliminary throw when tripped; a resetting lever to operate the restraining member, said lever having a closed cam slot; and means traversing said slot to shift said restraining member through a stroke of predetermined length.

24. In a calculating machine, the combination with a rotatable counter; and means to clear the counter; of a detent 55 to lock the counter against accidental turning; and a shiftable latch 58 to hold the detent effective.

25. In a calculating machine, the combination with a rotatable counter; a stop on the counter; and an abutment 49 shiftable into and out of the path of the stop; of a rocking detent 55 to lock the counter against accidental turning; and a latch 58 shiftable with the abutment, into and out of effective position, to lock the detent against rocking.

26. In a calculating machine, the combination with a toothed rotatable counter; and means to drive the counter; of a detent 55 to lock the counter against accidental turning, said detent having a slot 63 to embrace a tooth on the counter, and a nose 62 to fit the interdental spaces and center the counter; and a shiftable latch 58 to lock the detent in effective position.

27. In a calculating machine, the combination with a series of counters; means to drive said counters; and carrying mechanism to effect the transfer of tens to the adjacent counters; of swinging carry-controlling and resetting arms 33 connected with the carrying mechanism and having cam slots 42 therein; and a driven rod 18 to traverse said cam slots to rock said arms.

Signed this 8th day of July, 1913.

CHARLES V. WILGUS.

In the presence of—

E. M. DETRICK,
RALPH S. WARFIELD.
